Specification for Design.

Patented May 18, 1920.

Application filed December 1, 1919. Serial No. 341,813. Term of patent 14 years.

To all whom it may concern:

Be it known that I, GEORGE R. KUNKLE, a citizen of the United States, residing at Elyria, in the county of Lorain and State of Ohio, have invented a new, original, and ornamental Design for Phonograph-Casings, of which the following is a specification, reference being had to the accompanying drawing, forming part thereof.

The figure is an elevation of a phonograph casing, showing my new design.

I claim:

The ornamental design for a phonograph casing, as shown.

GEO. R. KUNKLE.
